ASH DISCHARGE FOR UNDERFEED STOKERS

Royce L. Beers, Birmingham, Mich., assignor to
Detroit Stoker Company, Monroe, Mich., a cor-
poration of Michigan

Application June 26, 1939, Serial No. 281,301

7 Claims. (Cl. 110—38)

The invention relates to automatic stokers for furnaces of that type comprising inclined longitudinally reciprocating grate bars along which the fuel is fed and ash discharge grates connected to the lower ends of said bars and movable therewith. The reciprocating grates are supported at their opposite ends upon rockable members and the lower rockable member also supports the ash discharge grates. To facilitate assembly and to permit of repair the grates must be readily engageable with or disengageable from the rockers and with certain constructions this is accomplished by providing open slots in the grates permitting of vertical engagement with the rocker bars on which they are supported. However, where there is any obstruction to the feeding of the fuel and the reciprocation of the grates, there is a tendency for the latter to lift out of engagement with the supporting rocker, thereby becoming inoperative.

It is one of the objects of the instant invention to obtain a construction which while permitting quick engagement or disengagement of the grates with the supporting rockers, also provides for interlocking so as to prevent accidental disengagement. A further object is to obtain a construction with which the incandescent fuel and ash supported on the ash discharge grates is kept out of contact with the furnace wall, so as to avoid fusion thereto. With these and other minor objects in view, the invention consists in the construction as hereinafter set forth.

In the drawings:

Figure 1 is a transverse section through a portion of a furnace provided with my improved stoker;

Figure 2 is a plan view thereof;

Figure 3 is a perspective view of the rocker member, fuel grates and ash discharge grates detached;

Figure 4 is an enlarged section similar to Figure 1, showing the manner of unlocking the grates from the rocker to permit disengagement thereof;

Figure 5 is an elevation of the tuyère for cooperating with the ash discharge grates.

In general construction the stoker to which my improvements are applied comprises a central retort A and inclined grate bars B extending therefrom toward opposite sides of the furnace, only one side being illustrated. The bars B are supported at their upper ends upon rocker bars C which are actuated by suitable mechanism (not shown). At their lower ends these bars also rest upon rocker bars D which in turn are pivot-

ally supported in bearings E. F are arcuate ash discharge grates having their upper ends supported on the rocker bars D and their lower ends connected by links G to crank arms H on a normally stationary rockshaft I. Thus, when the rocker bar C is actuated the grates B will be longitudinally reciprocated and the ash discharge grates F will be carried thereby, the lower ends moving with the links G about the pivotal connection H' to the cranks H. It is to be understood that there are stationary grate bars B³, Figure 2, alternating with the movable grate bars B and the effect of the reciprocation of the latter is to feed the fuel downward onto the grates F from the lower ends of which the ash is discharged.

It is usual to provide such furnaces with a chamber J beneath the grates which contains air at more than atmospheric pressure, and the rocker bar D in addition to its function of supporting the grates B, forms an air seal for said chamber. There is also a chamber K beneath the ash discharge grates F containing air at a lower pressure than that in the chamber J and supplied from the latter through a damper controlled port L. Thus, there is always an upward current of air passing about the grates B and F, which sufficiently cools the same to prevent burning out.

To accomplish the primary object of my invention I have constructed the rocker bar D and the discharge grates F so as to form an interlocking but pivotal engagement with each other. To this end the bars D are formed in short sections adapted to be arranged in alignment with each other and together extending the full length of the series of grates between the front and rear or bridge wall of the furnace. Each bar D has a web portion D' with interrupted cylindrical portions D² at the lower end thereof for engagement with the supporting bracket bearings E. These bearings have interrupted hooked portions E' for pivotally engaging and interlocking with the portions D². The spaces D³ intermediate said portions D² permit of aligning the latter with the hooked bearings E', after which an axial movement of the member D will complete the engagement. In this way the members D may be successively engaged with the bracket bearings E to extend from one end to the other of the series.

The members D are further provided at their upper ends with interrupted cylindrical portions D⁴ and in the spaces between these portions cylindrical portions D⁵ of smaller diameter. The

grate bars B which are hollow and preferably formed of complementary channeled sections have at their lower ends semi-cylindrical bearings B' which may be directly engaged with the bars D normally resting on the portions D⁵ thereof. The grate bars F are formed at their upper ends with hooked segments F' of an axial length less than the width of said bars, which segments extend circumferentially more than 180° and are of a radius for fitting the portions D⁴ and pivotally interlocking therewith. These hooked portions cannot, therefore, be directly engaged with the portions D⁴, but by first registering the portions F' with the smaller diameter portions D⁵ they may be engaged therewith, after which an axial movement will engage them with the portions D⁴. In this way, the members F are locked to the bars D so as to be held from accidental disengagement, while at the same time permitting a free pivotal action. The members F are of a width greater than the width of the grate bars B, so that they will overlap a plurality of said bars. The hooked portions F' are, however, substantially the width of the stationary grate bars and the portions F² on opposite sides of said hooked portions will overlap the movable grate bars substantially one-half their width. These overlapping portions F² are fashioned to engage external cylindrical segments B² on the grate bars B and in normal position will prevent the lifting of said grate bars out of engagement with the rocker bars D. If, however, the members F are drawn downward by the rocking of the cranks H so as to swing about the axis of the portions D⁴ and D⁵ of the bars D, this will place them in a position to clear the segments B² to permit the lifting off of the bars B.

To prevent the molten ash and clinker from adhering to the side wall of the furnace, I have provided a cooled member arranged opposite the lower end of the ash grates F and between which and said grates the ash is discharged into the chamber K. As shown in Figure 1, this member comprises a series of tuyères M secured in the furnace wall and projecting outward therefrom. As specifically illustrated, a channel beam N is placed in a recess in the furnace wall, said beam having a rib N' depending from its upper flange and a series of lugs N² projecting forward from its web portion having aligned apertures therein. Each tuyère has an inclined top portion M' and a central rearwardly extending web portion M² provided with a hood M³ for engaging with the rib N'. This web is also apertured in alignment with the apertures in the lugs N² for the insertion of a holding rod N³ which may be inserted from the front of the furnace to lock all of the tuyères to the channel beam. Thus, air from the chamber K will pass upward around and between the tuyères M to cool the same, as well as to support combustion of the partially consumed fuel above the grates and tuyères.

The parts being constructed and assembled as above described, they will normally operate as follows. The rocking of the rocker bars C will impart longitudinal movement to the grate bars B, which in turn will actuate the rocker bars D and ash discharge grates F. The lower ends of the latter will swing about the center H', the shaft I and cranks H being normally stationary. Inasmuch as the hooked portion F' of each ash discharge grate F is in engagement with the portion D⁴ of the rocker bar D, this will prevent any lifting of said member F out of engagement with the rocker. Also, as the portions F² of the

member F extend over the arcuate portions B² of the grate bars B they will prevent the lifting of the latter bars.

If at any time it is necessary to remove any of the grate bars B or ash discharge grates F this may be accomplished by manually rotating the shaft I to turn the cranks H downward. This, through the medium of the links G, will swing the ash discharge grates F downward to a position where the portions F' will clear the portions B² of the grate bars B. The latter bars may then be lifted off from the rocker bars D and C. The grate F may be disengaged by disconnecting the link G therefrom, after which it may be moved axially off from the portion D⁴ and onto the portion D⁵ of the rocker bar D. As the diameter of the portion D⁵ is less than that of the opening into the hook, the latter may be lifted out of engagement.

In the normal functioning of the apparatus the downward movement of the ash discharge grates F will effect the discharge of fine ash between the same and the tuyères M. It will also have the effect of breaking up the clinker, inasmuch as the upper surface of the grate F is toothed. If, however, any clinker is formed which cannot be discharged between the grate F and the tuyère M, the rockshaft I may be manually operated to swing the grate downward about the portion D⁴ of the rocker bar D, thereby enlarging the space between the grate and the tuyère.

What I claim as my invention is:

1. In a furnace including replaceable reciprocating grate bars and a rocker member for supporting said grate bars, of means for normally restraining vertical displacement of certain of said grate bars with respect to said rocker member while permitting of assembly and disassembly of the same said means comprising a segmental cylindrical bearing on the one and interrupted pivot on the other of said rocker member and grate bar, said bearing having an entrant slot of lesser width than the diameter of the pivot and said interrupted pivot permitting of movement normal to the axis thereof relative to said bearing into axial alignment therewith when the latter is in registration with said interruption.

2. In a furnace including replaceable reciprocating grate bars, a support and a rockable member intermediate said support and grate bars, of means for normally restraining vertical displacement of said grate bars with respect to said rocker member and support while permitting of assembly and disassembly of such parts, said means comprising segmental cylindrical bearings on certain of said grate bars and on said support, said bearings having entrant slots of lesser width than the internal diameter thereof, and interrupted pivots on said rocker member axially alignable and subsequently engageable with their corresponding bearings by a movement relative thereto normal to the axis while said bearings are in registration with interruptions.

3. In a furnace including replaceable reciprocating fuel supporting grate bars, aligned ash discharge members and a rocker member for supporting the adjacent ends of said aligned grate bars and ash discharge members, of means for normally restraining vertical displacement of said grate bars with respect to said rocker member while permitting assembly and disassembly of such parts comprising an interlocking pivotal connection between said ash discharge member

and rocker including a segmental cylindrical bearing on the one and an interrupted pivot on the other, said bearing having an entrant slot of lesser width than the diameter of the pivot 5 and being engageable by a movement transverse to the axis and an axial movement of one with respect to the other, a pivotal connection between said grate bar and rocker engageable by a relative movement transverse to the axis, and means 10 on said ash discharge member overlapping a portion of said grate member to restrain the same from disengagement in the normal relation of these parts, said means being disengaged by an abnormal rotation of said ash discharge member 15 about its pivotal connection with said rocker.

4. In a furnace including replaceable reciprocating grate bars, a support and a rockable member intermediate said support and grate bars, of means for normally restraining vertical displacement of said grate bars with respect to said 20 rocker member and support while permitting assembly and disassembly of such parts, said means comprising bearings on certain of said grate bars and on said support having entrance slots therein 25 of lesser width than the internal diameter of the bearings, and interrupted pivot portions on said rocker member permitting of relative movement normal to the axis thereof into axial alignment with said bearings when the latter are registered 30 with said interruptions and also engagement with said bearings by a relative axial movement.

5. In a furnace including replaceable reciprocating grate bars and a rocker member for supporting said grate bars, of means for normally restraining vertical displacement of said grate bars with respect to said rocker member while permitting of assembly and disassembly of the same, said means comprising alternate pivot portions of different radii on the upper end of said 35 rocker member, bearings on certain of said grate bars corresponding to the pivot portions of larger radius and having entrance slots of lesser width permitting movement normal to the axis over the pivot portions of smaller radius into axial alignment 40 with the larger radius portions and axial movement into engagement therewith, bearings on alternate grate bars corresponding to the pivot portions of smaller radius and engageable therewith by a movement normal to the axis, and 45 means on the first mentioned grate bars normally restraining displacement of the second mentioned grate bars but permitting disengagement thereof when said first mentioned grate bars are swung about their pivots to an abnormal 50 position.

6. In a furnace including replaceable reciprocating fuel supporting grate bars, aligned ash

discharge grate bars and a rocker member for supporting the adjacent ends of said aligned grate bars, of means for normally restraining vertical displacement of said grate bars with respect to said rocker member while permitting assembly and disassembly of the same, said means comprising alternate pivot portions of different radii on the upper end of said rocker member, bearings on said ash discharge grate bars corresponding to the pivot portions of larger 10 radius and having entrance slots of lesser width permitting movement normal to the axis over the pivot portions of smaller radius into axial alignment with the larger radius portions and axial movement into engagement therewith, bearings 15 on said fuel supporting grate bars corresponding to the pivot portions of smaller radius and engageable therewith by a movement normal to the axis, and means on the first mentioned grate bars which in normal position restrains displacement of the second mentioned grate bars but permits disengagement thereof when said first mentioned grate bars are swung about their pivots to an abnormal position.

7. In a furnace including replaceable reciprocating fuel supporting grate bars and aligned ash discharge grate bars, of a series of aligned transversely extending rocker members for supporting the adjacent ends of said grate bars, a series of spaced stationary bearings for supporting said 25 rocker members each bearing having an entrance slot of lesser width than the internal diameter of the bearing, said rocker members being formed with interrupted pivot portions at their lower ends successively engageable with said bearings 30 by a movement normal to the axis and axial movement relative thereto, each of said rocker members also having at its upper end alternate pivot portions of different radii, a bearing on each of said ash discharge grate bars corresponding 35 to the pivot portion of larger radius and provided with an entrance slot of lesser width, said bearings being engageable with said rocker members by a movement normal to the axis over the pivot portion of smaller radius and axial movement 40 onto the pivot portion of larger radius, a bearing on each of said fuel supporting grate bars engageable with said pivot portion of smaller radius by a movement normal to the axis thereof, and means on each ash discharge grate bar normally overlapping a portion on the adjacent fuel supporting grate bar to hold the same from vertical displacement, said overlapping means being disengageable by rotation of said ash discharge 45 grate bar about its pivot to an abnormal position.

ROYCE L. BEERS.
